Term of patent 3½ years

To all whom it may concern:

Be it known that I, Louis Katz, a citizen of the United States, residing in New York city, in the county of New York and State of New York, have invented a new, original, and ornamental Design for a Dress Ensemble, of which the following is a specification, reference being had to the accompanying drawings, forming part thereof.

Figure 1 is a front view of a dress ensemble showing my design.

Figure 2 is the rear view thereof.

Figure 3 is a front view of the dress of the ensemble shown in Figure 1.

The characteristic feature of my design resides in the combination on the specific ensemble disclosed of the specific spaced-apart bands of contrastingly colored embroidery arranged on the lower portion of the skirt and on the jacket, as shown.

I claim:

The ornamental design for a dress ensemble, substantially as shown and described.

LOUIS KATZ.
